Inventor:

W. E. Williams

UNITED STATES PATENT OFFICE.

WILLIAM ERASTUS WILLIAMS, OF CHICAGO, ILLINOIS, ASSIGNOR TO AMERICAN STEEL FOUNDRIES, OF CHICAGO, ILLINOIS, A CORPORATION OF NEW JERSEY.

AUTOMOBILE DISK WHEEL.

Application filed April 30, 1920. Serial No. 377,819.

To all whom it may concern:

Be it known that I, WILLIAM ERASTUS WILLIAMS, a citizen of the United States, a resident of Chicago, in the county of Cook and State of Illinois, have invented a new and useful Improvement in Automobile Disk Wheels, of which the following is a specification.

My invention relates to disk wheels adapted to receive pneumatic tires, and especially to the disk and rim construction.

Reference will be had to the accompanying drawing in which Figure 1 is a front elevation of the wheel.

Figure 2 is a partial diametrical section of the wheel.

Figure 3 is a modified form of the rim fastening.

Figure 4 is an enlarged detail of the demounting feature at the hub.

In the drawing 1 indicates an automobile hub, here shown as the front wheel. 2 indicates my disk and 3 indicates the main section of the rim and 4 indicates the companion flange of the rim.

The hub is provided with a special shaped flange 5 having the curved surfaces 6 and 7 and the straight portion 8.

The disk 2 is shaped to fit the curved portions 6 and 7 but is so shaped that there is clearance across the straight face 8 of the hub flange 5.

An annular clamping ring 9 is shaped to fit the disk opposite the curved surfaces 6 and 7 and is held in place by a series of screw studs 10 screwed on with special nuts 11 having within them the lock washers 12 which remain within the nuts when the latter are screwed off by reason of the dovetailed or under cut seat for the spring washers as is indicated by 13.

In clamping the disk to the hub as indicated, through the medium of the nuts 11, a tight snug fit is made on the curved surfaces 6 and 7 which thus relieve shearing strain on the stud screw 10 and permits a clearance around the said studs in the holes that pass through the disk for the entry of the studs through the disk.

On removing the nuts 11 the flange 9 and the disk 2 readily come off, owing to the easy release from the curved surfaces.

By shaping the flange of the hub and the inner annular surface of the disk to the shape of the curved surfaces 6 and 7 and

the straight portion connecting the same, I am able to press the disk to an exact shape for these surfaces, without having to machine the surface of the disk, which is a serious factor of saving in the manufacture of the wheels and in addition it gives rather sharp bearing surfaces in the curved region of 6 and 7 without at the same time making too great a depth through the assembly of the parts, which depth is paid for in the cost of the metal which I succeed in saving by reason of the construction shown.

The disk 2 has a peripheral annular portion fitting the interior surface of the rim and continuous with a broad annular conical fitting the outwardly converging conical flange of the rim is indicated, in order to permit the disk to be dished as indicated, presenting a concavé surface to the outside in order to resist skidding, and said conical zone merges by a long gentle curve in the disk portion of the disk.

A further feature of value obtained by inclining this flange 14 outward as indicated is to permit the dish of the disk as described, and also to permit a greater depth for the companion flange 4 in the distance marked "D" in Figure 2. The companion flange is secured to the main portion of the rim through the medium of a flange 15 which is secured by screws 16 engaging flange nuts 17 on the back of the disk. The inflation pressures of a pneumatic tire exert enormous deflecting strains, on this companion flange, which must be taken up by the screws 16. It is desirable to have as few of the screws 16 as is permissible for taking up the bursting strains of the inflation pressures of the tire tending to push off the companion flange 4 in a sidewise direction.

Thus the companion flange 4 becomes as it were a bridge from screw 16 to screw 16 and if this distance "D" is too small the flange will spring between the screws and thus it is almost necessary in order to have a perfectly safe flange, to have the depth "D" quite large, for if the internal flanges 14 and 15 extend in parallel relationship to the plain of the revolution of the wheel it lessens the amount of dish that may be given to the disk and further it crowds in upon the location of the air valve and fails to give sufficient clearance for proper access to the stem of the air valve on the

inside of the disk. But with the flanges inclined as I have shown, plenty of clearance is provided for the air valve stem and plenty of dish is permitted to the main disk 2 of the wheel.

10 The flange 14 of the main section 3 of the rim is turned over into a shoulder or flange 18 which registers and holds concentric the flange 15 of the companion flange 4 and thus relieves the screws 16 from shearing stress, which is a great desideratum.

15 In Figure 2 the screws 16 are placed in a line parallel with the axis of the wheel and embossed or raised portions 20 are provided for seats for the heads of the screws. The nuts 17 as shown in Figure 2 have little flanges 19 on their edges and are riveted through the disk and the flange 14 of the main rim and section 3, as indicated by 21.

20 In the detail, Figure 3, I show the screws passing through at right angles to the flanges 14 and 15 instead of being parallel with the axis of the wheel as is shown in Figure 2.

25 The inclination of the flanges 14 and 15 outward as is shown furnishes the further advantage that as the companion flange is secured home the pressure of the tire on that flange is partly taken up by the inclined contact surfaced between the flanges 14 and 15 and not necessarily all transmitted to the registering flange 18.

30 It is my intention to allow clearance for the screws 16 through the flange 15 of the companion flange so that no shearing strains will be put upon the said screws 16 in the road service of the rim, which is a great desideratum.

35 40 What I claim is:—

1. The combination with a two part rim having a divided cylindrical peripheral surface and provided with a broad conical flange at the line of division converging to

45 ward the outer end of the hub, of an outwardly concave disk gradually reversed in

direction and passing by a long gentle curve into an inwardly diverging conical zone fitting the conical flange, and means for rigidly connecting the flange and the closely fitting conical zone.

50 2. The combination with a circumferentially divided rim the two parts of which are provided with closely fitting, outwardly converging conical flanges, of an inwardly dished disk having its circumferential zone gradually reverse in direction and by a continuous gentle curve merging in a conical zone and closely fitting one of said flanges, and bolts passing said flanges and conical zone.

55 3. The combination with a rim made in two unequal, peripherally continuous rings connected by broad closely fitting marginal flanges converging toward the hub's outer end, of a disk having the side toward said end concave, its concave portion being reversed by a single bend and merged in a conical zone fitting within said flanges, and bolts passing through the flanges and disk binding all together, whereby strains are transmitted wholly through long gentle curves.

60 4. In a wheel of the class described, the combination with a wheel web, of a metal rim divided at some distance from each face of the wheel and having the meeting edges of the two parts provided, respectively, with inwardly extending flanges having their meeting faces inclined away from the central plane of the wheel, and the body of one flange being overlapped by said web, wedge-like nuts riveted to the web, and bolts parallel to the axis of the wheel, passing through said flanges and engaging said nuts, respectively.

65 Signed at Chicago, in the county of Cook and State of Illinois, this twenty-seventh day of April, 1920.

70 WILLIAM ERASTUS WILLIAMS.
